(57) **CLAIM**

The ornamental design for a training football, as shown and described.

DESCRIPTION

FIG. 1 is an isometric view of a training football for a right handed thrower embodying my new design, which includes hand shaped textured areas;

FIG. 2 is a right side elevational view thereof;

FIG. 3 is a front elevational view thereof;

FIG. 4 is a left side elevational view thereof;

FIG. 5 is a rear view thereof;

FIG. 6 is a top plan view thereof;

FIG. 7 is a bottom plan view thereof;

FIG. 8 is an isometric view of a training football for a left-handed thrower embodying my new design, which includes hand shaped textured areas;

FIG. 9 is a right side elevational view thereof;

FIG. 10 is a front elevational view thereof;

FIG. 11 is a left side elevational view thereof;

FIG. 12 is a rear elevational view thereof;

FIG. 13 is a top plan view thereof; and,

FIG. 14 is a bottom plan view thereof.
